UNITED STATES PATENT OFFICE

FLORAIN J. SHOOK AND CATO IVERSON, OF AKRON, OHIO, ASSIGNEES TO NATIONAL RUBBER MACHINERY COMPANY, OF AKRON, OHIO, A CORPORATION OF OHIO

VULCANIZER

Application filed July 11, 1930. Serial No. 467,195.

This invention relates to vulcanizers such as are employed for the manufacture of vehicle tires and inner tubes of rubber or rubber and fabric.

5 The general purpose of the invention is to improve upon existing vulcanizers as to ease, safety and efficiency of operation.

One object of the invention is to provide an improved vulcanizer of the balanced type 10 in which the vulcanizer sections are so connected that one counterbalances the other whereby the vulcanizer is opened or closed with comparative ease.

Another object of the invention is to provide 15 a vulcanizer of the balanced type in which one section is of such weight, as compared to the other, as normally to urge the vulcanizer sections to open position.

A further object of the invention is to provide 20 fluid pressure means for operating a vulcanizer of this type, including means for cushioning the movement of the vulcanizer sections.

25 A further object of the invention is to provide an improved means in said vulcanizer for effectively seating mold sections against each other under pressure to prevent the formation of a "rind" on the vulcanized articles, such means preferably exerting such 30 pressure independently of the means for closing the vulcanizer.

A further object of the invention is to provide 35 a simple locking device for holding the vulcanizer sections together during the application of heat and pressure to the mold.

A further object of the invention is to provide 40 effective means in a vulcanizer to prevent the blowing of a valve stem through the wall of an inner tube therein during vulcanization.

The foregoing and other objects of the invention are attained in the vulcanizer illustrated in the accompanying drawings and 45 described below. It is to be understood that the invention is not limited to the specific form thereof shown and described.

Of the accompanying drawings:

Figure 1 is a sectional elevation of a vulcanizer embodying the invention shown in

an open position with an inner tube inserted therein;

Figure 2 is a similar view showing the vulcanizer closed and locked with an inner tube 55 therein;

Figure 3 is a view on line 3—3 of Figure 2;

Figure 4 is a view on line 4—4 of Figure 2;

Figure 5 is a view on line 5—5 of Figure 2;

Figure 6 is a view on line 6—6 of Figure 5;

Figure 7 is a view on line 7—7 of Figure 5; 60

Figure 8 is a view on line 8—8 of Figure 2;

and

Figure 9 is a view on line 9—9 of Figure 1.

Referring to the drawings, the numeral 10 designates a suitable bed or base frame on 65 which a lower vulcanizer section or platen 11 is pivoted as at 12, 12 by arms 13, 13 to which the platen 11 is secured (see Figure 4). The platen 11 is adapted normally to seat by gravity on the bed frame 10, preferably in a forwardly sloping position (Figure 1), seats for the platen 11 on top of the frame 10 being indicated at 14.

The platen 11 is arranged to cooperate with 70 an upper platen 15 secured on arms 16, 16 which are pivoted at 17, 17 on frame 10, the pivot supports at 17 being slidably mounted in slots 18, 18 in the frame for limited movement therein for a purpose which will be 75 explained.

Arms 13 may be extended upwardly as at 80 13^a to form one member of a toggle, the other member of which may comprise links 19, 19 connected to downwardly extended portions 16^a, 16^a on arms 16, thus providing a toggle connection between the platens designed to hold the upper platen upwardly and rearwardly when the lower platen is resting on the bed frame (Figure 1) and adapted to cause the upper platen to swing downwardly 85 as the lower platen is swung upwardly to bring the vulcanizer sections into cooperation (Figure 2). The lower platen with the various parts carried thereon is heavier than the upper platen, with the result that it overbalances the upper platen so as normally to hold the vulcanizer open as shown in Figure 1.

For actuating the vulcanizer sections, fluid pressure cylinders 20, 20 may be pivoted on 90

- frame 10, as at 20^a, with the pistons 21 therein connected by rods 22 to downwardly extending portions 13^b on arms 13. A fluid pressure supply line 23 is connected to ducts 24 in head 20^b of cylinder 20, which ducts are connected by ducts 25 with ports 26 serving to admit fluid into the ends of the cylinders behind the pistons. Suitable check valves 27 are arranged in ducts 25 to open to pressure 10 in ducts 24 and to close to pressure in ports 26. Ducts 24 are also connected to ducts 28 which are connected by pipes 29 with ports 30 in the cylinders at points spaced from the heads 20^b to provide, in effect, dash pots in said cylinders between head 20^b and said points. Ports 31 in said heads 20^b are connected by pipes 32 to an adjustable relief valve 33. Heads 20^c of cylinder 20 have outlet ports 34 therein connected by pipes 35 to a relief valve 36 similar to valve 33. These heads also have ports 37 therein through which air is adapted to be drawn into the cylinders, these ports being closed by pressure within the cylinder by means of check valves 37^a. 15 Ports 38 in said cylinders at points spaced from heads 20^c are provided to produce a dash pot action between said ports and heads 20^c. 20 Each vulcanizer platen carries a mold section, platen 11 supporting a mold section 39 and platen 15 a mold section 40 which are arranged to cooperate when the vulcanizer is closed. These mold sections are preferably jacketed as shown to be heated by a fluid medium. The mold shown is designed to provide an annular molding cavity for vulcanizing inner tubes. 25
- The vulcanizer locking means comprises a rotatable bayonet plug 41 which may be arranged on the lower platen centrally of the mold section 39 and a bayonet socket 42 in the upper platen centrally of the upper mold section, these parts being provided with the usual interengaging lugs 43 and 44, respectively, so arranged as to permit insertion of the plug into the socket and then rotation of the plug therein to engage the lugs. The plug 41 may be arranged to be rotated by securing it on a shaft 45 rotatable by a crank 46 connected to a piston rod 47, the piston of which is operable in a cylinder 48 pivoted at 49 on the lower platen, said cylinder having fluid pressure connections 50 and 51 at both ends thereof whereby said piston is double acting. 50

The vulcanizer is constructed so that a comparatively heavy pressure may be applied to the mold when the vulcanizer is locked. This provision comprises an expandible, annular envelope or diaphragm 52 of flexible material, such as rubber, housed in an annular groove 53 in the face of the vulcanizer platen 11 over which is arranged a safety plate 54 shiftable in said groove, upward movement 55 of which is limited by stops 55, 55. In order

to prevent deterioration of the expandible diaphragm or envelope 52 by the heat of vulcanization, a composite asbestos and steel plate 56 (Figure 9) is arranged above plate 54 in groove 53 and is supported on plate 54 by spacer channel members 57 which provide an insulating air space beneath the asbestos and steel plate 56. The envelope 52 may be provided with a fitting 52^a, similar to an inner tube valve, by which a fluid under pressure may be supplied thereto to expand the same. 75

In an inner tube vulcanized as shown, it has been found that there is a tendency for the valve base within the tube to be forced more or less through the wall of the tube by the fluid pressure used to expand the tube against the mold surface. To prevent this, the upper mold section 40 may be provided with an extending lug or block 57 (see Figure 8) adapted to engage in a recess 58 in the other mold section 39 at a point on the inner periphery of the mold where the valve stem V of the tube may be brought through the mold, the block and recess being so designed as to fit about the valve stem, and a spring pressed pin 59 in block 57 is designed to grip the valve stem V. 80 85

The operation of the vulcanizer may be controlled either manually by suitable hand valves (not shown) or automatically by suitable time-controlling mechanism and valves operated thereby (not shown). In either case the sequence of operation may be as follows: 90

With the parts as shown in Figure 1, an inner tube or other article is mounted on the lower mold section 39. A fluid, such as air under pressure, is next supplied through heads 20^b into the cylinders 20, causing the pistons to travel to the left and thus through rods 22 and arms 13 swinging the lower section 11 upwardly and through arms 13 and links 19 swinging the upper vulcanizer section downwardly into cooperation. As the mold sections 39 and 40 move together, the pistons 21 pass over the ports 38 and the left ends of the cylinders thus provide dash pots from which the fluid passes through ports 34, piping 35 and relief valve 36. This cushions the closing of the vulcanizer. Fluid is then supplied to cylinder 48 to actuate rod 47 and crank 46 to turn plug 41 in socket 42 and thereby the vulcanizer is locked. 100 105 110 115

Air or other fluid under pressure is next admitted through fitting 52^a to envelope 52 to expand the same and force the lower mold section tightly against the upper mold section under such pressure as to prevent the formation of a rind on the tube when vulcanized. The shifting pivotal mounting of section 15 on the frame 10 at 18 relieves the toggle connections 13 and 19 of stresses by reason of the pressure between the mold sections during vulcanization, all of which 120 125 130

stresses are assumed by the lugs 43 and 44 of the bayonet locking means.

When the cure has been completed, the pressure in envelope 52 is relieved, the locking device released and the vulcanizer opened by relieving the fluid pressure in back of pistons 21. Gravity causes the lower vulcanizer section to swing downwardly and it in turn, through the linkage, swings the upper vulcanizer section upwardly. Air finds access to cylinder 20 in front of piston 21, first through port 36 and then through ports 38, and when the pistons pass the ports 30, the right ends of the cylinders 20 become dash pots, the fluid pressure being relieved slowly through valves 33. The finished article may now be removed and a raw article inserted for a subsequent vulcanizing operation.

It will be apparent that if for any reason the pressure should fall on the fluid pressure lines, the vulcanizer if shut and locked would not be affected, if being opened or shut or if shut and unlocked it will merely open, and that it is impossible for the vulcanizer to close except upon positive operation thereof. Accordingly, likelihood of injury to workmen is reduced to a minimum.

Modifications of the invention may be resorted to without departing from the spirit thereof or the scope of the appended claims.

What is claimed is:

1. A vulcanizer comprising lower and upper pivoted members, a toggle mechanism connecting the lower member to the upper member whereby when the lower member is lowered the upper member is raised, said lower member having a preponderance of weight so as to overbalance the upper member whereby the vulcanizer normally assumes an open position under the action of gravity, means for supporting the lower member when the vulcanizer is open, means for closing the vulcanizer, cooperating means on the vulcanizer members for locking the members together when closed, and means on one vulcanizer member for applying pressure on a mold in said vulcanizer independently of said closing means.

2. A vulcanizer comprising lower and upper members, a mechanism connecting the lower member to the upper member whereby when the lower member is lowered the upper member is raised, said lower member having a preponderance of weight so as to overbalance the upper member whereby the vulcanizer normally assumes an open position under the action of gravity, means for supporting the lower member when the vulcanizer is open, means for closing the vulcanizer, cooperating means on the vulcanizer members for locking the members together when closed, and means on one vulcanizer member for applying pressure on a mold in said vulcanizer independently of said closing means.

3. A vulcanizer comprising pivoted lower

and upper members, connections between the members for causing the members to move toward or from each other when one of said members is moved, the lower member being of greater weight so as to overbalance the upper member normally to hold the vulcanizer open, and fluid pressure means engaging said lower member for closing the vulcanizer, said means being adapted to cushion the opening of the vulcanizer when the fluid pressure is relieved.

4. A vulcanizer comprising pivoted lower and upper members, connections between the members for causing the members to move toward or from each other when one of said members is moved, the lower member being of greater weight so as to overbalance the upper member normally to hold the vulcanizer open, and fluid pressure means engaging said lower member for closing the vulcanizer.

5. A vulcanizer including a pair of pivotally mounted members of different weights so connected that the weight of the heavier one will effect operation of the other whereby the vulcanizer will normally be open, means for closing the vulcanizer, means in the vulcanizer for applying pressure between the members independently of said closing means, and means for locking the vulcanizer in its closed position.

6. A vulcanizer comprising lower and upper members, an arm supporting the lower member, a pivotal mounting for said arm, a second arm supporting the upper member, a second pivotal mounting for said second arm, a link between said arms providing a toggle whereby when the lower member is lowered the upper member is raised, said lower member overbalancing the upper member normally to hold the vulcanizer open, means connected to the first arm for closing the vulcanizer, means cooperating when the vulcanizer is closed for locking the vulcanizer, and means for exerting pressure between the vulcanizer sections independently of said closing means.

7. A vulcanizer comprising lower and upper members, an arm supporting the lower member, a pivotal mounting for said arm, a second arm supporting the upper member, a second pivotal mounting for said second arm, a link between said arms providing a toggle whereby when the lower member is lowered the upper member is raised, said lower member overbalancing the upper member normally to hold the vulcanizer open, means connected to the first arm for closing the vulcanizer, and means cooperating when the vulcanizer is closed for locking the vulcanizer.

8. A vulcanizer comprising lower and upper members, an arm supporting the lower member, a pivotal mounting for said arm, a second arm supporting the upper member, a second pivotal mounting for said second arm, a link between said arms providing a

toggle whereby when the lower member is lowered the upper member is raised, said lower member overbalancing the upper member normally to hold the vulcanizer open, and means connected to the first arm for closing the vulcanizer.

9. A vulcanizer comprising lower and upper members, an arm supporting the lower member, a pivotal mounting for said arm, 10 a second arm supporting the upper member, a second pivotal mounting for said second arm, a link between said arms providing a toggle whereby when the lower member is lowered the upper member is raised, said lower member overbalancing the upper member normally to hold the vulcanizer open, and means for closing the vulcanizer.

10. The combination in a vulcanizer of relatively movable pivoted vulcanizer sections, connections between the sections for moving one vulcanizer section when the other vulcanizer section is moved, one of said sections being of preponderant weight so that the sections normally move to an open position, and fluid pressure means for moving the vulcanizer sections together.

11. The combination in a vulcanizer of relatively movable pivoted vulcanizer sections, and connections between the sections for moving one vulcanizer section when the other vulcanizer section is moved, one of said sections being of preponderant weight so that the sections normally move to an open position.

35 12. The combination in a vulcanizer of relatively movable pivoted vulcanizer sections, connections between the sections for moving one vulcanizer section when the other vulcanizer section is moved, one of said sections being of preponderant weight so that the sections normally move to an open position, fluid pressure means for moving the vulcanizer sections together, means for locking the sections together, and means in one section for applying pressure on a mold therein when the vulcanizer is locked.

13. The combination in a vulcanizer of relatively movable pivoted vulcanizer sections, connections between the sections for moving one vulcanizer section when the other vulcanizer section is moved, one of said sections being of preponderant weight so that the sections normally move to an open position, means for locking the sections together, and means in one section for applying pressure on a mold therein when the vulcanizer is locked.

60 14. The combination with a balanced vulcanizer comprising pivotally mounted members of different weights linked together so as normally to open, of means for closing said members, means for locking said members closed, and means comprising a fluid 65 expansible element in one of said members

for exerting pressure between said members when locked.

15. The combination with a balanced vulcanizer comprising pivotally mounted members of different weights linked together so as normally to open, of means for locking the members together, and means comprising a fluid expansible element in one of said members for exerting pressure between said members when locked. 75

16. The combination with a balanced vulcanizer comprising pivotally mounted members of different weights linked together so as normally to open, an annular mold carried by said members, and means comprising 80 interengaging bayonet plug and socket centrally of the mold for locking the members together.
